UNITED STATES PATENT OFFICE

2,147,627

VEHICLE ENDGATE

Frank G. Bulick, Worthington, Minn.

Application April 8, 1937, Serial No. 135,809

1 Claim. (Cl. 296—52)

This invention relates to an endgate for use in connection with wagon bodies and the like, an object being to dispense with the use of rods or cleats such as commonly employed for holding endgates in position and to provide a simple, compact and efficient means whereby the endgate can be securely but removably held in proper position without the employment of any separate parts likely to become misplaced, such as rods, etc., or the employment of cleats which tend to become clogged and interfere with the placing of the endgate.

With the foregoing and other objects in view which will appear as the description proceeds, the invention consists of certain novel details of construction and combinations of parts herein-after more fully described and pointed out in the claim, it being understood that changes may be made in the construction and arrangement of parts without departing from the spirit of the invention as claimed.

In the accompanying drawing the preferred form of the invention has been shown.

In said drawing—

Figure 1 is a rear elevation of a wagon box or body provided with an endgate such as constitutes the present invention.

Figure 2 is a horizontal section through the parts shown in Figure 1, said section being taken on the line 2—2, Figure 1.

Referring to the figures by characters of reference 1 designates the side walls of the wagon body or box and 2 designates the endgate which, in the present instance, is provided with an outlet opening 3 which can be closed normally by a hinged door 4.

A folded plate is attached to each of the side walls 1. This plate includes an intermediate portion 5 bent to form a tube of double thickness, the inner thickness 6 merging into an angular shoulder portion 7 which abuts against the adjacent end of the wall 1 and then merges into a wing 8 which laps the inner side of the wall. The outer thickness 9 of the tube 5 merges into a wing 10 which extends along the outer side of the wall 1, the two wings 8 and 10 being fastened securely together and to the wall by means of bolts 11 or the like extending therethrough. It will be noted that the fold 12 of the plate is spaced from the shoulder 7 so as to provide a slot 13 which opens into the tube 5 as shown.

To each side portion of the endgate 2 is attached another folded plate 14. This plate is bent at the folded portion to provide an outward flange 15 of double thickness merging into a rolled portion 16 shaped to fit snugly within one of the tubular portions 5. From the flange

15 the two thicknesses of the plate are extended at right angles, one thickness terminating in a wing 17 mounted on the outer side of the endgate 2 while the other thickness merges into a rearwardly extending shoulder 18 which laps the adjacent edge of the endgate and then merges into a wing 19 extending along the inner surface of the endgate. The two wings are joined together and to the endgate by bolts 20 or the like extending therethrough.

One of these plates is attached to each side portion of the endgate and the wings, as shown in Figure 1, can be so shaped as to clear the opening 3. The shoulder portions 18 are spaced apart such a distance as to fit snugly between the wings 8 on the side walls of the wagon body or box and the angular projecting portions of the folded plates 17 are proportioned to fit within the slots 13 as well as within the tubular portions 5.

It will be apparent that when it is desired to remove the endgate, it is merely necessary to slide it upwardly. This will withdraw the portion 16 from the tubular portions 5 so that the endgate is thus entirely free from the wagon body. When it is desired to place the endgate in secure position at the end of the body, it is merely necessary to lower it so that the portions 16 and 15 will slide downwardly within the portions 5 and the slots 13 until the endgate is ultimately seated on the floor of the wagon body.

Obviously with this type of connection it becomes unnecessary to use guide and holding cleats such as commonly employed or to use rods or similar devices which are easily misplaced. The connection shown and described is very simple, compact and efficient and will not readily get out of order.

What is claimed is:

The combination with a vehicle body, of folded plates straddling the walls of the body and having folded portions projecting beyond the ends of the walls, said folded portions providing slotted tubes of two thicknesses contacting throughout their areas and a shoulder spaced from the tubes, an endgate seated entirely between the side walls of the body, and folded plates straddling and secured to the sides of the endgate, each of said plates having a folded portion extended therefrom and shaped to provide a tube of two thicknesses contacting throughout their areas and slidably into and adapted to fit snugly within the adjacent slotted tube on the wagon body, the interfitting tubes on the gate and body being located behind and in alignment with the side walls of the body and back of the planes occupied by the front and back surfaces of the gate.

FRANK G. BULICK.
